Attorneys.

UNITED STATES PATENT OFFICE.

BENJAMIN J. HASTINGS, OF TAUNTON, MASSACHUSETTS, ASSIGNOR TO HASTINGS SIGNAL & EQUIPMENT COMPANY, OF BOSTON, MASSACHUSETTS, A CORPORATION OF MASSACHUSETTS.

BRIDGE-WARNING DETACHER AND REPLACER.

Application filed April 7, 1923. Serial No. 630,491.

To all whom it may concern:

Be it known that I, BENJAMIN J. HASTINGS, a citizen of the United States, residing at Taunton, county of Bristol, State of Massachusetts, have invented a certain new and useful Improvement in Bridge-Warning Detachers and Replacers, of which the following is a specification, reference being had therein to the accompanying drawings.

10 Railroads are required to provide bridge warnings, so-called, erected in such manner as to be suspended over the track to serve as a warning to brakemen on top of freight cars of the near approach to the bridge. 15 These warnings usually consist of a series of wire hangers pivotally connected with an arm extending crosswise of the track, these hangers being usually only a few inches apart and pivotally connected with the arm 20 in such manner that they may swing in a direction lengthwise of the track. These wires are usually a foot or so in length and there is secured to the lower end of each wire a rope which hangs down a sufficient 25 distance, so that, if a brakeman is standing or sitting on the top of a freight car at the time he reaches the warning, the ropes will strike him in ample time to permit him to flatten himself on the top of the car 30 to avoid striking the bridge. The lower ends of these ropes usually reach down to about sixteen feet above the top of the rail, but the exact height varies somewhat with different railroads.

35 The upper end of the wire is usually formed with an eye which is connected with the cross arm by some suitable means. Sometimes these wires get bent, and for this reason and for other causes it becomes 40 necessary to take down the wires in order to straighten them or to substitute others or to replace the ropes which are suspended from the wires. It was formerly necessary for the workmen to use a ladder and climb 45 up to the cross arm in order to detach the wires. In Patent No. 1,207,550, dated December 5, 1916, granted to me, I showed and described a special form of hanger to 50 be attached to the cross arm, and with which the wire was connected in such manner that the wire might be engaged therewith or disconnected therefrom, by an operative standing on the ground, by using

a pole with a suitable attachment for manipulating the hanger. The object of 55 the present invention is to provide an improved attachment for a pole for readily handling the drop wire so as to connect it with the hanger on the crossbar or to 60 detach it therefrom.

65 The invention will be fully understood from the following description when taken in connection with the accompanying drawings, and the novel features thereof will be pointed out and clearly defined in the 70 claims at the close of this specification.

Fig. 1 is a side elevation of a device embodying the invention attached to a pole.

Fig. 2 is a front elevation viewed from the right-hand side of Fig. 1. 75

Fig. 3 is a side elevation taken from the opposite side from Fig. 1.

Fig. 4 is a plan view of Fig. 1.

Fig. 5 is a front elevation showing the device in use just as it is about to insert 75 one of the telltale drop wires into the hanger.

Fig. 6 is a side elevation showing the parts in the same position as in Fig. 5.

Fig. 7 is a front elevation similar to Fig. 80 5 but in the position after the eye of the wire hanger has been engaged with the hanger.

Fig. 8 is a side elevation similar to Fig. 6 but with the parts in the position shown 85 in Fig. 7.

Fig. 9 is a side elevation showing the device detached from the telltale after the telltale has been connected with the hanger, the clamping jaws of the device being still 90 engaged with the wire hanger of the telltale just about to strike the loop of the rope in the downward descent.

Fig. 10 is a side elevation showing two 95 of the telltales connected with hangers on the crossbar and showing in connection with an intermediate hanger and telltale the device embodying the invention in connection with the latch as it appears just after the telltale has been released. 100

Fig. 11 is a side elevation partly in section showing the spring seated plunger and the clamp.

Referring now to the drawings: On the under side of the arm 3 which extends over 105 the track are secured a plurality of hangers

A. These hangers as shown in the drawings are similar to the hangers shown and described in my said former Patent No. 1,207,550.

5 The hanger A has a head 4 provided with suitable means for attaching it to the arm 3. The telltale members each consist of a drop wire 7 and a rope 8 hanging from the drop wire. The said telltale members are detachably connected with the hangers a. The head 4 is formed with a vertical slot 6 extending up from the under side, said vertical slot being of only slightly greater width in one direction than the thickness 15 of the wire 7 but is of sufficient width in the other direction so that the eye 9 formed at the upper end of the drop wire may be easily entered up into the slot 6, as shown in Fig. 10. The said slot 6 preferably extends 20 up into the head a distance about equal to the full length of the eye 9 so that the full length of the eye may be introduced into the slot. Preferably the slot is open at the sides part way up but not for the full 25 height.

One side wall of the slot 6 is formed with a pair of ears 11, 11 extending at right angles to said wall, and with a slot 10 through said wall and between said ears, said slot 10 30 intersecting the slot 6 at right angles thereto. A latch or hook member 12 is pivoted on a pin 13 between said ears 11. Said latch has an arm 14 which, in its normal position, extends entirely across the slot 6 and has an 35 arm 15 which projects some distance beyond the outer edges of the ears as shown in the drawings. The latch 12 may be turned on its pivot so as to swing the arm 14 upward entirely out of the slot 6, as shown in Fig. 40 10. A stop is provided so that said arm 14 cannot be turned up beyond a certain distance, preferably just enough for the arm to be swung up out of the slot and there is also a stop to prevent the arm 14 falling below a 45 certain point so that in the lowermost position of the arm 14, it will extend crosswise of the slot. The stop mechanism for thus limiting the downward movement of the arm 14 is formed by the shoulder 16 of the wall 50 17 which connects the two ears 11, 11. This shoulder is engaged by the upper side of a shoulder on the arm 15 when the arm 14 is turned down, thus forming a stop to limit the downward turning of the arm 14.

55 When the latch is in its normal position with the arm 14 extending crosswise of the slot 6, the arm 15 will engage the under side of the said shoulder 16. When the latch is turned so as to swing the arm 14 up out of the slot 6, the shoulder 18 of the arm 14 60 will strike against the inside face of the wall 17 and thereby limit the upward turning of the arm 14.

65 Preferably the arm 14 overbalances the arm 15 of the latch, the said latch being free

to turn on its pivot so that the excess weight of the arm 14 over the weight of the arm 15 will cause the arm 14 to normally remain in its downward position crosswise of the slot. It is obvious that a spring or any other suitable equivalent could be employed to retain the said arm 14 normally in its downward position.

70 When it is desired to engage the eye 9 of the drop wire 7 with the hanger, the eye 9 75 of the drop wire will be inserted into the slot 6 from the underside and pushed up, the upper end of the eye thereby pushing up the arm 14, turning it on its pivot until the upper end of the eye rides by the end of the 80 arm 14, whereupon the weight of the arm 14 will then cause it to drop back through the eye and crosswise of the slot 6, as shown in Fig. 10, so that the wire will be hung on the arm 14. Whenever it is desired to release the drop wire, the arm 15 will be pulled down and the arm 14 will be tilted up and back out of the slot 6. By reason of the outwardly curved end of the arm 14, the eye of the drop wire will slide off the arm 14 and 90 drop out of the hanger.

95 The object of the present invention is to provide a suitable device which may be attached to the end of a pole whereby an operative standing on the ground may readily connect the drop wire with the hanger or disengage it therefrom. A device embodying the invention is shown in the drawings and is as follows: A tubular socket member 20 is adapted to be fitted over the end of a 100 pole 21. Connected with the said socket member are two leaves 22, 22 forming clamping jaws which normally lie close together and are capable of being sprung apart at their outer edges. Said jaws are provided 105 with outwardly flaring wings 23, 23 at their outer edges to provide a ready entrance for the drop wire as will be hereinafter explained.

110 Preferably said clamping jaws are made integral with the tubular socket member 20, the whole being made of spring sheet metal which is bent to the required shape under tension and the two jaws are kept normally closed by rivets 24 or other suitable means. 115 Preferably the said jaws widen out from the bottom upwards being upwardly inclined on the outer edge for the purpose as will be hereinafter described.

120 The said two jaws are each formed with a vertical concave bend or groove 25 in their inner faces, the said two concave portions being complementary to each other to form a pocket to receive the drop wire 7 when the jaws are spread open.

125 The shank of the drop wire may be inserted between the two jaws by guiding it laterally through the passage between the two flaring wings 23, 23, and by a slight lateral pressure of the wire it will spread apart 130

the said two jaws until the wire reaches the pocket formed by the two concave grooves 25, the eye of the drop wire being in a plane substantially parallel with the plane of the 5 jaws. The strength of the spring in the jaws is sufficient to hold the drop wire clamped in this position. When the drop wire is thus mounted between the jaws, the pole may be raised by the operative to bring 10 the eye of the drop wire into the slot 6 of the hanger and pushed upward until the eye of the drop wire tips up the latch far enough for the upper end of the eye to ride on to the upper side of the arm 14 when the latch will 15 drop back into locking position. The pole may then be moved to cause the disengagement of the jaws from the drop wire.

Preferably means are provided for guiding the drop wire to more readily accomplish the engagement of the drop wire with the hanger. The means which are provided are as follows (see Fig. 11): Secured to one side of one of the spring jaws is a tubular member or barrel 26 lying parallel 20 with the tubular socket member 20. Also attached to the said jaw is a second tubular member 27 lying parallel with the tubular member 26. A plunger member is provided, preferably formed out 25 of a single wire bent so as to form a horizontal head 28 and two leg members 29 and 30, said leg members being engaged respectively with the two tubular guides 26 and 27, said plunger being vertically slidable 30 in said tubular guide members. A coil spring 31 is enclosed in said tubular guide member 26 and surrounds the plunger leg 29, one end of said spring being seated upon a shoulder 32 in said tubular member, the 35 other end of said spring bearing against a stop 33 on said plunger leg. The tension of said spring is such that it normally holds the head of said plunger raised at some distance above the jaw, as shown in 40 Fig. 11. The plane of the two plunger legs 29 and 30 is slightly to one side of the plane of the two jaws but parallel therewith leaving a narrow space between the plane of the plungers and the plane through 45 the eye of the hanger slightly more than the thickness of the back wall 34 of the slot 6. In utilizing the guide member, the hanger should be inserted between the jaws so that the eye 9 will be some distance above 50 the upper edge of the jaws, substantially as high as the upper edge of the head 4 of the plunger member, with the plane of the eye of the drop wire parallel with the plane of the two plunger members. With the 55 parts in this position, the operator will then hold the pole upright, reaching it up into position so that the eye 9 will enter the slot 6 and the head 28 of the plunger will be on the outer side of the wall 34 60 of the hanger, so that the eye of the drop

wire and the head of the plunger will straddle the said wall 34 which thus serves as an additional guide to center the drop wire. See Figs. 5 and 6. Now when the pole is pushed up the head of the plunger will engage 70 the under side of the crossbar 3 or of the flange on the hanger, which stops the further upward movement of the plunger. As the pole is pushed further up the spring in the barrel of the plunger guide 75 will yield to allow the movement of the pole, and the jaws mounted on the pole will slide upward on the plunger and carry the drop wire until the eye of the drop wire is engaged with the latch. See Figs. 7 and 80 80. The eye of the drop wire will tip the latch on its pivot and allow the drop wire to be engaged on the upper side of the latch. The pole should then be pulled down until the lower ends of the inclined faces 85 of the wings engage the rope at the lower end of the drop wire, and then during the continued downward pull of the pole and by reason of the upward inclination of the wings as well as their flaring arrangement 90 the rope will ride on the inner faces of the flaring wings, which will act as a sort of cam to pull the wire out from between the spring jaws. See Fig. 9 in which the wings are just about to engage the rope. 95

In order to aid in disengaging the drop wire from the hanger I attach to one of the jaws a loop member 35 which may be engaged with the outer projecting arm 15 of the hanger to thereby pull down said arm 100 and turn up the latch arm 14 to disengage it from the eye of the drop wire. Preferably this loop member is formed of a single wire bent intermediate its ends in 105 such manner as to form a loop portion 35, the ends being twisted together to form a shank 36 which is secured by soldering or otherwise to one of the side jaws of the clamping member. Preferably this loop member is formed so as to have a straight 110 upper edge 36 substantially at right angles to the plane of the plunger members 29, 30, said loop member extending somewhat above the head 28 of the said plunger members. The purpose of thus making the head 36 of the loop member 35 at right angles to the plane of the head 28 of the plunger members is to enable the said loop member 115 to be used as a guide when the drop wire is to be assembled with the hanger by sliding said head along on the face of the crossbar so as to aid in positioning the jaws and the drop wire while the pole is stretched up at arms length. See Figs. 5 and 6. 120

What I claim is:

1. In a device of the character described, two cooperating clamping members mounted on a holder, said clamping members being adapted to yieldingly hold a drop wire, and a guide member extending above said 130

clamping members to guide the positioning of the drop wire with relation to a hanger with which it is to be connected.

2. In a device of the character described, two cooperating clamping members mounted on a holder, said clamping members being adapted to yieldingly hold a drop wire, and a spring seated guide member extending above said clamping members to guide the positioning of the drop wire with relation to a hanger with which it is to be connected.

3. In a device of the character described, two cooperating clamping members mounted on a holder, said clamping members being adapted to yieldingly hold a drop wire, and a guide member extending above said clamping member to guide the positioning of the drop wire with relation to a hanger with which it is to be connected, said guide extending upwardly in a plane parallel with the drop wire when held by the said clamping member and spaced slightly apart therefrom.

25 4. In a device of the character described, two cooperating clamping members mounted on a holder, said clamping members being adapted to yieldingly hold a drop wire, a guide member extending above said clamping members to guide the position of the drop wire with relation to a hanger with which it is to be connected, and a second guide member which extends upwardly above said first guide member and has a head which lies in a plane transversely of the plane of the said clamping members and is adapted to aid in positioning the drop wire and said first guide member with relation to a hanger for the drop wire.

40 5. In a device of the character described, two cooperating clamping members mounted on a holder, said clamping members being adapted to yieldingly hold a drop wire, a guide member extending above said clamping members to guide the positioning of the drop wire with relation to a hanger with which it is to be connected, and a member extending above the said clamping members having a loop at its upper end.

55 6. In a device of the character described, two cooperating spring clamping members normally held closed under tension, said clamping members being capable of being spread open at one side against the tension of the spring, the side edges of said clamping members adjacent the open side terminating in wings which flare away from each other to form a guide to the entrance between the said clamping members, said clamping members increasing in width from the bottom toward the top by an outward upward flare on the edge which forms the entrance to the clamping members.

60 7. A bridge warning detacher and replacer having spring clamping members to

yieldingly hold a bridge warning drop wire and a guide mounted adjacent said clamping members adapted to guide the positioning of the drop wire with relation to a hanger with which the drop wire is to be connected.

8. A bridge warning detacher and replacer having spring clamping members to yieldingly hold a bridge warning drop wire and a guide mounted adjacent said clamping members adapted to guide the operator in positioning the drop wire with relation to a hanger with which the drop wire is to be connected, and a member carried by said holder having means for tripping the drop wire from its hanger.

9. In a device of the character described, two cooperating spring clamping members normally held closed under tension, said clamping members being capable of being spread open at one side against the tension of the spring, a socket member for attaching the device to a pole, and a guide member mounted on one side of one of the clamping members in a plane parallel with and slightly spaced apart from the plane of the clamping members.

10. In a device of the character described, two cooperating spring clamping members normally held closed under tension, said clamping members being capable of being spread open at one side against the tension of the spring, a socket member for attaching the device to a pole, and a spring seated guide member mounted on one side of one of the clamping members in a plane parallel with and slightly spaced apart from the plane of the clamping members.

11. In a device of the character described, two cooperating spring clamping members normally held closed under tension, said clamping members being capable of being spread open at one side against the tension of the spring, a socket member for attaching the device to a pole, and a guide member consisting of a spring seated plunger rod mounted in guides on the face of one of the clamping members and having a head which lies in a plane parallel with the plane of the said clamping members and spaced a slight distance apart therefrom.

12. In a device of the character described, two cooperating spring clamping members normally held closed under tension, said clamping members being capable of being spread open at one side against the tension of the spring, a socket member for attaching the device to a pole, and a guide member consisting of a wire rod bent to form two parallel downwardly extending legs and a straight top, guides mounted on the side of one of the clamping members to receive the legs of the said guide member, and a spring seat for said guide rod, the top of the guide lying in a plane parallel with the

plane of the clamping members and spaced slightly apart therefrom.

13. In a device of the character described, two cooperating spring clamping members normally held closed under tension, said clamping members being capable of being spread open at one side against the tension of the spring, a socket member for attaching the device to a pole, and a guide member consisting of a wire rod bent to form two parallel downwardly extending legs and a straight top, guides mounted on the side of one of the clamping members to receive the legs of the said guide member, a

spring seat for said guide rod, the top of 15 the guide lying in a plane parallel with the plane of the clamping members and spaced slightly apart therefrom, and a loop member having a stem which is secured to the other clamping member and extends upwardly therefrom, said loop member extending somewhat above the top of said guide member, the plane of said loop member extending transversely of the plane of the jaws of the guide member. 20 25

In testimony whereof I affix my signature.

BENJAMIN J. HASTINGS.
